UNITED STATES PATENT OFFICE.

ALBERT W. GIFFORD, OF WORCESTER, MASSACHUSETTS.

TWEEZERS.

SPECIFICATION forming part of Letters Patent No. 223,444, dated January 13, 1880.

Application filed September 10, 1879.

To all whom it may concern:

Be it known that I, ALBERT W. GIFFORD, of the city and county of Worcester, of the State of Massachusetts, have invented a new and useful Improvement in Tweezers combined with Cutting Implements or Knives; and I do hereby declare the same to be described in the following specification and represented in the accompanying drawings, of

10 which—

Figure 1 is a side view, Fig. 2 an edge view, and Fig. 3 a longitudinal section, of a combined knife and tweezers provided with my invention. Fig. 4 is a side view of the sliding 15 knife which is applied to the tweezers. Fig. 5 is an edge view, and Fig. 6 a side view, of the connection-guide, to be hereinafter described.

My invention relates to a combined tweezers 20 and knife; and it consists in the combination of the aforesaid connection-guide with the shanked tweezers and the slotted shanked knife or tool arranged to slide between the shanks of the tweezers.

25 My invention further consists in one or each of the tweezers-shanks curved inward or made to act as a spring to hold the knife-blade in place when it is either within or drawn out of the space between the said shanks.

30 In the drawings, the elastic jaws *a a* of the tweezers *A* are represented as provided with thin and long metallic shanks *b b*, between which the shank *c* of the knife *B* is arranged. Lengthwise in such shank *c* is a slot, *d*, within 35 which is the bar *e* of the connection-guide *C*. This guide consists of a thin bar, *e*, and four studs, *f*, projecting from it at its ends in manner as represented. The bar is a little thicker than the shank of the knife. The studs *f* go 40 through the shanks of the tweezers-jaws, and are riveted down or upset thereon, so as to

hold the tweezers and knife in connection, the slot in the shank of the knife being of sufficient length to admit of the blade *k* being forced back so as to be wholly between the 45 shanks *b b*, or of being drawn out from between them. Each of such shanks *b* curves in near its outer end, as shown at *l*, whereby it not only operates to prevent the knife-blade, when back in the tweezers, from accidentally extending or working out from them, but when the blade is out they, by firmly grasping the knife-shank, prevent the blade from accidentally working back into the tweezers.

A small projection, *m*, at the back of the 55 blade-shank enables a person by his finger to move the shank longitudinally between the shanks of the tweezers-jaws.

The front edge of the knife-blade shank I usually provide with file-teeth, to enable it to 60 be used in filing the edge of a finger-nail after such nail may have been trimmed by the knife.

The connection-guide, by being a little thicker than the knife-shank, enables the latter to readily move lengthwise between the shanks of the 65 tweezers-jaws, which, being curved or turned in near their outer ends, answer purposes as hereinbefore stated.

I claim as my invention in the combined knife and tweezers as follows, viz: 70

1. The combination of the connection-guide *C* with the shanked tweezers-jaws and the slotted shanked tool or knife, all being arranged and applied substantially as set forth.

2. The shank or shanks *B* of the tweezers, 75 bent in so as to hold the knife-blade in place, as described, when in either of its extreme positions.

ALBERT W. GIFFORD.
